CLAIM

I claim the ornamental design for a printer, as shown and described.

DESCRIPTION

FIG. 1 is a front perspective view of a first embodiment of a printer showing my new design;

FIG. 2 is a rear perspective view showing the design of FIG. 1;

FIG. 3 is front view showing the design of FIG. 1;

FIG. 4 is a rear view showing the design of FIG. 1;

FIG. 5 is a first side view showing the design of FIG. 1;

FIG. 6 is a second side view showing the design of FIG. 1;

FIG. 7 is a top view showing the design of FIG. 1;

FIG. 8 is a bottom view showing the design of FIG. 1;

FIG. 9 is a front perspective view of a second embodiment of a printer showing my new design;

FIG. 10 is a rear perspective view showing the design of FIG. 9;

FIG. 11 is front view showing the design of FIG. 9;

FIG. 12 is a rear view showing the design of FIG. 9;

FIG. 13 is a first side view showing the design of FIG. 9;

FIG. 14 is a second side view showing the design of FIG. 9;

FIG. 15 is a top view showing the design of FIG. 9;

FIG. 16 is a bottom view showing the design of FIG. 9;

FIG. 17 is a front perspective view of a third embodiment of a printer showing my new design;

FIG. 18 is a rear perspective view showing the design of FIG. 17;

FIG. 19 is front view showing the design of FIG. 17;

FIG. 20 is a rear view showing the design of FIG. 17;

FIG. 21 is a first side view showing the design of FIG. 17;

FIG. 22 is a second side view showing the design of FIG. 17;

FIG. 23 is a top view showing the design of FIG. 17;

FIG. 24 is a bottom view showing the design of FIG. 17;

FIG. 25 is a front perspective view of a fourth embodiment of a printer showing my new design;

FIG. 26 is a rear perspective view showing the design of FIG. 25;

FIG. 27 is front view showing the design of FIG. 25;

FIG. 28 is a rear view showing the design of FIG. 25;

FIG. 29 is a first side view showing the design of FIG. 25;

FIG. 30 is a second side view showing the design of FIG. 25;

FIG. 31 is a top view showing the design of FIG. 25;

FIG. 32 is a bottom view showing the design of FIG. 25;

FIG. 33 is a front perspective view of a fifth embodiment of a printer showing my new design;

FIG. 34 is a rear perspective view showing the design of FIG. 33;

FIG. 35 is front view showing the design of FIG. 33;

FIG. 36 is a rear view showing the design of FIG. 33;

FIG. 37 is a first side view showing the design of FIG. 33;

FIG. 38 is a second side view showing the design of FIG. 33;

FIG. 39 is a top view showing the design of FIG. 33; and,

FIG. 40 is a bottom view showing the design of FIG. 33. The broken lines depict portions of the article that form no part of the claimed design.
